UNITED STATES PATENT OFFICE.

ROBERT W. WALLACE, OF SAN FRANCISCO, CALIFORNIA.

BOILER-FEEDER.

No. 821,683.

Specification of Letters Patent.

Patented May 29, 1906.

Application filed July 12, 1905. Serial No. 269,352.

To all whom it may concern:

Be it known that I, ROBERT W. WALLACE, a citizen of the United States, residing at San Francisco, in the county of San Francisco and State of California, have invented certain new and useful Improvements in Boiler-Feeders; and I do hereby declare the following to be a full, clear, and exact description of the invention, such as will enable others skilled in the art to which it appertains to make and use the same.

This invention relates to devices for feeding water to steam-boilers; and it consists in the novel construction and combination of the parts hereinafter fully described and claimed.

In the drawings, Figure 1 is a vertical section through the boiler-feeder. Fig. 2 is a sectional plan view taken on the line $x-x$ in Fig. 1. Fig. 3 is a detail sectional view of the ball-valve.

A is a reservoir for feed-water. This reservoir is steam-tight, and B is the inlet-pipe for the feed-water, provided with a check-valve b of any approved construction, which prevents the water from flowing backward in the pipe B.

C is a heating-coil arranged in the reservoir. The exhaust-steam of a steam-engine is preferably arranged to pass through this coil and heat the water in the reservoir; but the water may be heated in the reservoir by any other approved means.

D is an automatic air-escape valve mounted on the reservoir and arranged to let out the air when water is admitted to the reservoir through the pipe B. This valve D has a casing provided with a cylinder d , in which a piston c is slidable. A passage c' is provided at one end of the cylinder which connects it with the reservoir, and a passage d' or opening is provided at the other end of the cylinder, which connects it with the atmosphere.

E is a spring which normally presses the piston toward the passage c' , and e represents one or more small holes in the piston which permit the air to pass from one end of the cylinder to the other.

The piston c is provided with a valve e' at one end, which is normally open; but when the piston is moved against the pressure of the spring E it closes the outlet-opening or passage d' . When water is introduced into the

reservoir through the pipe B, the air is expelled through the automatic air-escape valve D; but when steam is subsequently admitted to the reservoir it forces the piston in the cylinder against the pressure of the spring, so as to close the outlet-opening, because the hole in the piston is of such small area that it does not prevent the steam from operating the piston.

F is a chamber secured to the bottom of the reservoir A. A pipe f connects this chamber with the boiler above its water-level, and a second pipe f' connects the said chamber with the boiler below its water-level.

F' is a dotted line indicating the mean water-level of the water in the boiler and in the chamber F.

G is a casing secured in the upper part of the chamber F. This casing has a passage g , which communicates with the lower part of the reservoir A, and a second passage g' , which communicates with the upper part of the reservoir A by means of a vertical pipe G'.

H H' are two valves, or a double valve. The upper and smaller valve H normally closes an opening from the chamber F to the said passage g' , and when opened admits steam from the chamber F to pass into the passage g' and up through the pipe G'.

The lower and larger valve H' normally prevents water from entering the chamber F from the reservoir through the passage g . A partition h between the two passages prevents the steam and water from mixing. I is a lever which is connected to the said valves H H' by a pin h' , and i is a pin which pivots the said lever to a lug on the under side of the casing G.

The free end portion of the lever I is pivotally connected with a piston J by means of the link i' . The piston J is slidable in a cylinder J', secured to the lower part of the chamber F. The upper end of this cylinder is in free communication with the steam-space of the chamber F. The lower end of the cylinder J' is provided with a passage j .

K is a three-way plug-valve which is connected to the passage j , and j' is a pipe which connects the said plug-valve with the atmosphere. An opening k in the casing of the plug-valve permits communication to be established between the lower end of the cylinder J' and the steam-space of the chamber F. An arm or lever m is provided for operating

the plug of the said plug-valve, and is provided with a ball or float m' in the chamber F.

M is a spring below the piston J, which normally holds the valves H H' closed.

5 M' is a cover at one side of the chamber F, which affords access to its interior, so that the cylinder J' and the casing G can be secured in position.

N is a pipe which connects the steam-space 10 of the chamber F with the lower end of the cylinder J', and n is a three-way plug-valve provided with an operating-handle n' and arranged in the said pipe N. The casing of this plug-valve is provided with an opening 15 o, so that the lower part of the cylinder J' can be connected with the atmosphere.

A pipe P is arranged to connect the reservoir A direct with the pipe j', which supplies water to the boiler, and p is a stop-valve, 20 which normally closes the passage through the pipe P.

The operation of the boiler-feeder is as follows: When a supply of hot water has accumulated in the reservoir and the level of the 25 water in the boiler is reduced so that the float descends to the position shown in Fig. 1, the lower end of the cylinder J' is placed in direct communication with the atmosphere by means of the passage j, plug-valve K, and 30 pipe j'. The pressure of the steam in the chamber F presses the piston downward in its cylinder against the pressure of the spring beneath it, and the valves H H' are opened. The upper valve H admits steam from the 35 chamber F to the upper part of the reservoir A, so that the pressure in the reservoir and in the boiler is equalized, and the automatic air-escape valve D is closed, as hereinbefore described. The water in the reservoir passes 40 the valve H' into the chamber F and thence to the boiler by the pipe j' until the boiler is filled with water by gravity up to its normal level and the float is raised. When the float is raised, it turns the three-way plug-valve, 45 so that the lower end of the cylinder J' is placed in communication with the steam-space of the chamber F, and the spring then raises the piston and closes the valves H H'.

The pipe N and plug-valve n are provided 50 so that the devices can be operated by hand at any time, and the pipe P and valve p are provided for use in filling an empty boiler.

What I claim is—

1. In a boiler-feeder, the combination, with 55 a steam and water chamber provided with boiler connection pipes at different levels, of a cylinder having an open upper end arranged inside the said chamber and having also a passage for connecting its lower end with the 60 atmosphere, a float-valve arranged inside the said chamber and controlling the said passage, a piston in the said cylinder, a reservoir arranged above the said chamber, and valve mechanism also arranged inside the

said chamber and connected with the said 65 piston and operating to control the flow of steam and water between the said chamber and reservoir.

2. In a boiler-feeder, the combination, with a steam and water chamber provided with 70 boiler connection pipes at different levels, of a cylinder having an open upper end arranged inside the said chamber and having also a passage for connecting its lower end with the atmosphere, a three-way valve arranged inside the said chamber and controlling the said passage and admitting steam from the said chamber to the lower part of the cylinder, a lever and float operating the said valve, a double valve for steam and water also arranged inside the said cylinder, a reservoir arranged above the said chamber and controlled by the said double valve, a piston in the said cylinder, and lever-connecting mechanism also arranged inside the said chamber 75 between the said double valve and the said piston.

3. In a boiler-feeder, the combination, with a chamber arranged at the water-level of a boiler and provided with pipes for connecting it with the boiler above and below its mean water-level respectively, of a cylinder having its upper end in constant communication with the said chamber and provided with a passage for connecting its lower end 90 with the atmosphere, a float-valve arranged in the said chamber and controlling the said passage automatically, a piston slidable in the said cylinder, valve mechanism connected with the said piston and operating automatically 95 to equalize the pressure in the said chamber and reservoir and to admit water from the said reservoir to the said chamber when the mean water-level is reduced, and a hand-operated valve arranged outside the 100 said chamber and placing the lower end of the said cylinder in communication with the atmosphere.

4. In a boiler-feeder, the combination, with a chamber arranged at the water-level of a 105 boiler and provided with pipes for connecting it constantly and directly with the boiler above and below its mean water-level respectively, of a reservoir arranged above the said chamber, a casing provided with a passage 110 connecting the lower part of the reservoir with the said chamber and having also a passage and a pipe for connecting the steam-space of the said chamber with the upper part of the said reservoir, portions of the said 115 passages being arranged to overlap each other and the said casing being secured inside the said chamber, two valves connected together and controlling the said passages, and means for operating the said valves.

5. In a boiler-feeder, the combination, with a chamber provided with boiler connections which maintain the water in the said cham-

ber constantly at the same level as the water in the boiler, of a water-reservoir arranged above the said chamber, valve mechanism arranged inside the said chamber and operating to control the flow of water from the said reservoir to the said chamber, and a cylinder also arranged inside the said chamber and provided with a float-valve and intermediate connections also arranged inside the

said chamber for operating the said valve to mechanism.

In testimony whereof I have affixed my signature in the presence of two witnesses.

ROBERT W. WALLACE.
